CLAIM

The ornamental design for a cleaning element for a robotic vacuum, as shown and described.

DESCRIPTION

FIG. 1 is a bottom view of a cleaning element for a robotic vacuum showing our new design;

FIG. 2 is a top view thereof;

FIG. 3 is a left view thereof;

FIG. 4 is a right view thereof;

FIG. 5 is a front view thereof;

FIG. 6 is a rear view thereof;

FIG. 7 is a bottom perspective view thereof; and,

FIG. 8 is a top perspective view thereof.
